UNITED STATES PATENT OFFICE.

LEOPOLD KAIN, OF NEW YORK, N. Y.

DESIGN FOR A BOTTLE.

SPECIFICATION forming part of Design No. 21,669, dated June 28, 1892.

Application filed May 21, 1892. Serial No. 433,914. Term of patent 3½ years.

To all whom it may concern:

Be it known that I, LEOPOLD KAHN, of the city, county, and State of New York, have invented and produced a new and original Design for a Bottle, of which the following is a full, clear, and exact specification.

My design has relation to that variety of bottles which are inclosed in a covering of metallic substance.

Reference is to be had to the accompanying drawing, forming a part of this specification, in which the figure is a perspective view of a bottle, showing my design.

The essential feature of my design is the curved stem-like figures and the side branches extending from the stems and terminating in flower-like figures, the upper flower-like figures falling over and upon the bottle-top.

The main stems are arranged parallel with

each other and are curved upward from the bottom to the top of the bottle, and produced on opposite sides of the main stems are smaller branches, which terminate in flower-like figures, and the upper flower-like figures fall over the top of the bottle-body. Interposed between the several stems and the flower-like figures are numerous leaf-like figures, which partially fill the spaces between the stems, giving to the whole an appearance of open lace-work.

I claim—
The design for a bottle herein shown and described.

LEOPOLD KAIN.
